UNITED STATES PATENT OFFICE

2,691,446

OIL FILTER

Ernest E. Murray, Birmingham, Mich.

Application May 10, 1952, Serial No. 287,177

14 Claims. (Cl. 210—196)

1

The present invention relates to improvements in filters of the type adapted to remove foreign materials from liquids and particularly relates to filters for removing metal particles from cutting liquids.

Filters are now employed which are disposed adjacent metal cutting machines for removing metal particles from the cutting liquids employed in the cutting operations of such machines and in which cloth is disposed over the top of a rectangular receptacle and supported by a wire mesh. The cloth is pulled from one end of the receptacle across the top and beyond the opposite end of the receptacle. Gravity alone is employed for causing the liquid to pass through the cloth, leaving the metal particles embedded in the cloth. The cutting liquid, which is relatively expensive, is recirculated for the cutting operation after it has been filtered. The difficulties with these prior filters are that they are expensive, take up excessive floor space, are slow and are not efficient in that liquid containing the metal particles spills over the sides of the cloth into the receptacle without passing through the cloth and without the metal particles being removed from the liquid.

According to the present invention, an improved filter is provided which has a greater capacity for efficiently removing the metal particles from the cutting fluid relative to the amount of floor space occupied. It is also relatively less expensive than such prior constructions. One of the important features of the invention is the provision of a machine which employs a filtering element which is tubular in cross section. Such filtering element is flexible and is preferably formed of a cloth, such as cheese cloth, in which the edges are sewed together to form an elongated tube. The element is rolled to provide a substantial supply or length of the material for use and is so disposed on the machine that the tubular element is extended from the center of the machine, outwardly around the edges thereof so that all of the liquid containing the metal particles must pass through the filtering element in reaching the recirculating tank. As the filtering cloth becomes clogged with the metal particles, fresh surfaces are provided by advancing the cloth from the supply roll. The machine may be used to remove metal particles, either magnetic or nonmagnetic, or other foreign materials carried by a liquid.

One of the primary objects of the present invention is to provide an improved filter of the type mentioned having a higher capacity and efficiency than prior structures relative to the

2

amount of floor space employed. A further object of the invention is to provide an improved filter of the type mentioned which is economical to manufacture relative to prior constructions.

Other objects of the present invention will become apparent from the following specification, the drawings relating thereto and from the claims hereinafter set forth.

10 In the drawings in which like numerals are used to designate like parts in the several views throughout:

Figure 1 is a perspective view of a filter mechanism embodying features of the present invention;

Fig. 2 is a top, perspective view of a portion of the structure shown in Fig. 1;

Fig. 3 is a top plan view, with parts broken away, of the structure shown in Fig. 1;

20 Fig. 4 is a cross sectional view, with parts in elevation, taken substantially along the line 4—4 of Fig. 1;

Fig. 5 is an enlarged, part elevational view, taken substantially along the line 5—5 of Fig. 4;

25 Fig. 6 is an enlarged, cross sectional view, taken substantially along the line 6—6 of Fig. 4;

Fig. 7 is a diagrammatic view of part of the control mechanism in relation to the liquid level within the filter mechanism; and

Fig. 8 is a schematic diagram of the electrical circuit employed with the controls of the present invention.

Referring to the drawings, a roll of the filtering material is indicated at 1 and such roll is rotatably supported on a spindle 2, the ends of which are supported within the forked upper ends of uprights 3. Uprights 3 are in turn supported on a horizontal bar 4, the ends of which are connected to uprights 5 which are mounted on the floor. The filtering cloth is unrolled and brought downwardly as indicated at 6 and such filtering cloth 6 is preferably a cheese cloth of a desired mesh. The edges of the cloth are sewed together so that when distended or opened it is tubular in form and of a substantial length in order to provide an adequate operating supply.

A filtering mechanism, generally indicated at 7, comprises an upstanding metal drum or receptacle 8 having an annular opening 9 at the top thereof.

50 An openwork or foraminous support 10 is disposed within the receptacle 8 adjacent the open top thereof and such support 10 is generally frusto-conical in shape and is in the embodiment illustrated, a sheet metal member having a plurality of uniformly spaced openings entirely over

the area thereof. The outer end terminates in a reversed annular flange 11 and the periphery is substantially the same as that of the opening 9 so that the flange hangs over the opening to mount the support 10 onto the receptacle 8. The outer peripheral edge of the support 10 is rounded so as to present a smooth rounded surface over which the filtering cloth is drawn, as will become more apparent from the later description.

The support 10 is corrugated or curved over a portion of its length, as best seen in Figs. 3, 4, and 6, with the corrugations being of gradually increasing depth from the large end of the support 10 toward the smaller end thereof. Thus the support is so shaped that the linear distance around the periphery of any plane normal to the center line of the support is substantially uniform from top to bottom. Thus the linear distance around the support of any such plane is substantially the same as the linear distance around the outer or large peripheral edge of the support 10.

The circumference of the tubular filtering element 6 is also substantially the same as that of the opening 9, or the circumference at the outer periphery of the support 10, and with the support shaped as indicated above, the cloth of the element 6 will lie against the curved surfaces and will not bunch up. Thus, substantially the entire periphery of the tubular filter 6 will uniformly lie against the surface of the support 10 and be exposed for filtering purposes. As the filtering cloth is drawn upwardly over the support, a substantially uniform area of the cloth is presented for filtering purposes from the central portion of the support to the outer periphery.

The cutting liquid carrying the metal particles from the cutting tool is carried through a conduit 12 to an annular outlet conduit 13. The conduit 13 has an annular slot or opening 14 (Fig. 4) formed therein so that as the unfiltered liquid is pumped from the cutting machine it is discharged through the slot 14. The annular conduit 13 is disposed within the receptacle 8 adjacent to but spaced from the support 10 and disposed centrally thereof.

The tubular filtering element 6, which is disposed above the filter 7, passes through and under the annular conduit 13 and then upwardly and outwardly along the support 10 and over and around the opening 9 and down along the sides of the receptacle 8. The element 6 is bunched as it passes through the ring 13 but opens up as it lies against the support 10 and is passed around the top annular opening of the receptacle completely therearound.

From the structure so far described, it is apparent that the unfiltered cutting fluid must pass through the filtering cloth 6 and through the openings of the support 10 so that the clean and filtered liquid drops into the bottom of the receptacle 8 and any metal particles are embedded in the cloth of the filtering material and thus are removed from the liquid.

As the filter cloth becomes clogged with the metal particles, it will be appreciated that the liquid cannot pass through so that, according to the present invention, the filter cloth 6 is advanced around the outside of the receptacle 8 pulling clean and fresh filtering cloth from the roll 1 so that such clean filtering cloth is presented against the support 10 as the advanced cloth has become clogged.

Means are provided for advancing the filtering cloth and such means comprise a plurality

of rubber covered rollers 16 which are rotated and which engage the filter cloth 6 on the outside of the receptacle 8 adjacent the upper edge thereof to pull the cloth around the opening 9.

The rollers 16 are driven and are mounted upon a drive shaft supported in the forked end of an upstanding support arm 17. The arm 17 is rotatably mounted upon a drive shaft 18 which is supported in a bracket 19. The brackets 19 for each of the rollers are mounted on an annular angle iron 20 which is disposed around the receptacle 8 in spaced relation thereto. The annular angle support 20 is in turn supported by upstanding frame members 21 which in turn are connected to the sides of a pan 22 disposed on the floor around the receptacle 8. Additional supports for the annular support 20 may be provided by frame members 23 which may be fixed to the upstanding roller supports 5.

The drive shaft on which each of the rollers 16 is mounted has a sprocket 24 connected to one end thereof and a drive chain 25 interconnects the sprocket 24 with another sprocket 26 which is connected to the shaft 18. Thus when the shaft 18, for each of the rollers 16, is rotated, the roller 16 would be correspondingly driven through the sprockets 24 and 26 and chain 25.

A flexible or universal drive is provided for the shafts 18 and such drives include universal couplings or universal drive connections 27. One of the drive shafts 18 is connected through a universal coupling 28 with the driven shaft of a gear reducer 29 which in turn is driven by an electric motor 30, through a belt and pulley connection 31. Thus the single motor serves to drive all of the rollers 16 simultaneously through the flexible drive connections between the interconnected rollers 16.

The rollers 16 are mounted on the pivoted arms 17 and are resiliently urged toward the receptacle 8 and into engagement with the filter cloth by means of coil springs 32 which have their opposite ends connected to the outer end of pins 33 on the adjacent arms 17.

Elongated backing or bearing rollers 34 are rotatably mounted on brackets disposed on the outer surface of receptacle 8 adjacent the top thereof in such a position that they would be engaged by the rollers 16. The tubular filtering cloth is disposed between the rollers 34 and 16, and as the rollers 16 rotate, in the direction of the arrow in Fig. 4, the cloth 6 will be engaged and gripped between rollers 16 and 34 to cause the material 6 to be advanced downwardly on the outside of the receptacle 8, pulling more fresh cloth from the roll 1 and outwardly from the center of the support 10.

As the cloth 6 passes the rollers 16, it is still tubular in form and, so that the contaminated cloth can be readily dispensed with and to facilitate the feeding or advancing operation, it is split or slit longitudinally by means of a rotating cutter 36. Such cutter 36 is in the form of a disc cutter mounted on a suitable support under the feed rollers 16. The cutter 36 is driven by means of an electric motor 37.

In order to speed the separation of the foreign material from the liquid and to cause the liquid to pass through the filtering cloth into the collecting chamber at the bottom of the receptacle 8, a blower or exhaust fan 38 is disposed under the cutter 36 and has a conduit 39 which communicates with the interior of the receptacle 8 below the cutter 36 and under the support 10 through an opening 40. The fan or blower 38

is driven by an electric motor 41. Thus, by reducing the pressure within the chamber 8 under the support 10, the liquid is forced through the filtering cloth 6 and thus increases the efficiency of the unit.

A recirculating pump 43 communicates with the interior of the receptacle 8 adjacent the bottom thereof and has suitable inlet and outlet conduits leading back to the cutting machine for recirculating the cleaned cutting liquid.

Controls are provided for actuating the feeding, cutting, and exhaust means so that clean surfaces of the filtering cloth 6 will be presented as needed for most efficient operation. Such control means are best shown in Figs. 2, 7, and 8. A float 46 is mounted on a float arm 47 which in turn is pivotally mounted to a control box 48 mounted on the upstanding portion of conduit 12. The arm 47 has another arm integral therewith which pivots with the arm 47 as the float 46 rises and falls and such arm is connected to mercury switches MS1 and MS2 within the control box. The mercury switches and the motors 30, 31, and 41 are electrically interconnected as shown by the electrical diagram in Fig. 8. The electrical elements, per se, form no part of the present invention as they are well known in the art, and the motors are energized or de-energized through the action of the float 46 on the mercury switches MS1 and MS2, depending upon the level of the liquid above the filtering cloth 6 and support 10.

Referring to Fig. 7, such levels are diagrammatically illustrated, with line 48 indicating low level, line 49 indicating intermediate level, and line 50 indicating high level. With the float 46 between low level 48 and intermediate level 49, MS1 is closed so that the exhaust motor 41 is energized and MS2 is open so that feed motor 30 and cutter motor 31 are de-energized. Thus the exhaust fan 38 will act to supplement the action of gravity and draw the liquid through the filtering cloth until the cloth becomes so clogged that the liquid level rises above it. When the liquid level reaches line 49, the float 46 will open MS1, thus de-energizing the blower motor. As the level rises to high level 50, the float 46 will act to close MS2, thus energizing the advancing motor 30 and the slitting motor 31. The rollers 16 are then driven to advance the cloth 6 downwardly along the outside of the receptacle 8, pulling the cloth off the roller 16 and presenting clean and fresh filtering surfaces. Liquid may then easily pass through the cloth, and when it drops to line 49, MS1 is closed and MS2 is open, thus energizing the exhaust fan and de-energizing the feed and cutter motors. This cycle is repeated as the liquid continues to be fed into the filter.

Formal changes may be made in the specific embodiment of the invention described without departing from the spirit of the invention, the scope of which is commensurate with the appended claims.

What is claimed is:

1. In a filtering device for separating foreign material from liquid, a receptacle having an open top, support means disposed above said top adapted to support a supply of foraminous flexible filtering material, an open-work support disposed within said receptacle adjacent said open top and adapted to support said filtering material, said filtering material being adapted to be disposed completely around the upper edge of said receptacle and down the outside thereof, feed means disposed around the outside of said recip-

tacle and adapted to engage said filtering material to advance said material outwardly around said upper edge, and means to supply liquid containing foreign material into said receptacle 5 above said openwork support.

2. In a filtering device for separating foreign material from liquid, a receptacle having an annular open top, support means disposed above said top adapted to support a supply of foraminous flexible tubular filtering material, an open-work support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to advance said material outwardly around said upper edge, and means to supply liquid containing foreign material into said receptacle above said openwork support.

3. In a filtering device for separating foreign material from liquid, a receptacle having an annular open top, support means disposed above said top adapted to support a supply of foraminous flexible tubular filtering material, an open-work support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to advance said material outwardly around said upper edge, a cutter disposed under said feed means and adapted to slit said tubular filtering material, and means to supply liquid containing foreign material into said receptacle above said openwork support.

4. In a filtering device for separating foreign material from liquid, a receptacle having an annular open top, support means disposed above said top adapted to support a supply of foraminous flexible tubular filtering material, an open-work support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to advance said material outwardly around said upper edge, an exhaust fan communicating with said receptacle under said open-work support, and means to supply liquid containing foreign material into said receptacle above said openwork support.

5. In a filtering device for separating foreign material from liquid, a receptacle having an annular open top, support means disposed above said top adapted to support a supply of foraminous flexible tubular filtering material, an open-work support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to advance said material outwardly around said upper edge, a cutter disposed un-

der said feed means and adapted to slit said tubular filtering material, an exhaust fan communicating with said receptacle under said openwork support, and means to supply liquid containing foreign material into said receptacle above said openwork support.

6. In a filtering device for separating foreign material from liquid, a receptacle having an annular open top, support means disposed above said top adapted to support a supply of foraminous flexible tubular filtering material, an openwork support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to advance said material outwardly around said upper edge, a cutter disposed under said feed means and adapted to slit said tubular filtering material, an exhaust fan communicating with said receptacle under said openwork support and under said cutter, and means to supply liquid containing foreign material into said receptacle above said openwork support.

7. In a filtering device for separating foreign material from liquid, a receptacle having an annular open top, support means disposed above said top adapted to support a supply of foraminous flexible tubular filtering material, an openwork support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to advance said material outwardly around said upper edge, a cutter disposed under said feed means and adapted to slit said tubular filtering material, an exhaust fan communicating with said receptacle under said openwork support and under said cutter, a first motor operatively connected to said feed means, a second motor operatively connected to said cutter, a third motor operatively connected to said exhaust fan, control means for operating said motors in response to the level of the unfiltered liquid above said filtering material within said receptacle, and means to supply liquid containing foreign material into said receptacle above said openwork support.

8. In a filtering device for separating foreign material from liquid, a receptacle having an annular open top, support means disposed above said top adapted to support a supply of foraminous flexible tubular filtering material, an openwork support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to move said material outwardly around said upper edge, a cutter disposed under said feed means and adapted to slit said tubular filtering material, an exhaust fan communicating with said receptacle under said openwork support and under said cutter, a first motor operatively connected to said feed means, a second motor operatively

connected to said cutter, a third motor operatively connected to said exhaust fan, control means for operating said motors in response to the level of the unfiltered liquid above said filtering material within said receptacle, said control means including float controlled electric switches and circuit controls to energize said third motor and de-energize said first and second motors when said float is between low and intermediate level and to de-energize said third motor when said float is at intermediate level and energize said first and second motors when said float is at high level, and means to supply liquid containing foreign material into said receptacle above said openwork support.

9. In a filtering device for separating foreign material from liquid, a receptacle having an annular open top, support means disposed above said top adapted to support a supply of foraminous flexible tubular filtering material, an openwork support disposed within said receptacle adjacent said open top and adapted to support said filtering material, said filtering material being adapted to be disposed from the center outwardly and completely around the upper edge of said receptacle and down the outside thereof, roller feed means disposed around the outside of said receptacle and adapted to engage said filtering material to advance said material outwardly around said upper edge, and means to supply liquid containing foreign material into said receptacle above said openwork support.

10. In a filtering device for separating foreign material from liquid, a receptacle having an annular open top, support means disposed above said top adapted to support a supply of foraminous flexible tubular filtering material, an openwork support disposed within said receptacle adjacent said open top and adapted to support said filtering material, said filtering material being adapted to be disposed from the center outwardly and completely around the upper edge of said receptacle and down the outside thereof, feed means including spaced rollers disposed around the outside of said receptacle and adapted to engage said filtering material to advance said material outwardly around said upper edge, means to rotate said rollers, means to resiliently urge said rollers to said receptacle into engagement with said filtering material, and means to supply liquid containing foreign material into said receptacle above said openwork support.

11. In a filtering device for separating foreign material from liquid, a receptacle having an annular open top, support means disposed above said top adapted to support a supply of foraminous flexible tubular filtering material, a frustoconical openwork support disposed within said receptacle adjacent said open top and adapted to support said filtering material, said filtering material being adapted to be disposed from the center outwardly and completely around the upper edge of said receptacle and down the outside thereof, feed means disposed around the outside of said receptacle and adapted to engage said filtering material to advance said material outwardly around said upper edge, and means to supply liquid containing foreign material into said receptacle above said openwork support.

12. In a filtering device for separating foreign material from liquid, a receptacle having an annular open top, support means disposed above said top adapted to support a supply of foraminous flexible tubular filtering material, a frustoconical openwork support disposed within said re-

ceptacle adjacent said open top and adapted to support said filtering material, said support being shaped so that the linear distance around the periphery of any plane normal to the center is substantially uniform from top to bottom, said filtering material being adapted to be disposed on said support from the center outwardly and completely around the upper edge of said receptacle and down the outside thereof, feed means disposed around the outside of said receptacle and adapted to engage said filtering material to advance said material outwardly around said upper edge, and means to supply liquid containing foreign material into said receptacle above said openwork support.

13. In a filtering device for separating foreign material from liquid, a receptacle having an annular open top, support means disposed above said top adapted to support a supply of foraminous flexible tubular filtering material, an openwork support disposed within said receptacle adjacent said open top and adapted to support said filtering material, means to supply liquid containing foreign material into said receptacle above said openwork support, said last named means including an annular supply duct disposed centrally of said receptacle and through and under which such tubular filtering material is adapted to pass from the center outwardly and completely around the upper edge of said receptacle and down the outside thereof, and feed means disposed around the outside of said receptacle and adapted to en-

gage said filtering material to move said material outwardly around said upper edge.

14. In a filtering device for separating foreign material from liquid, a receptacle having an annular open top, support means disposed above said top adapted to support a supply of foraminous flexible tubular filtering material, a frusto-conical openwork support disposed within said receptacle adjacent said open top and adapted to support said filtering material, means to supply liquid containing foreign material into said receptacle above said openwork support, said last named means including an annular supply duct disposed centrally of said receptacle and said openwork support and through and under which said tubular filtering material is adapted to pass from the center outwardly and completely around the upper edge of said receptacle and down the outside thereof, and feed means disposed around the outside of said receptacle and adapted to engage said filtering material to move said material outwardly around said upper edge.
